(57) **CLAIM**

The ornamental design for the nozzle for textile machine, as shown and described.

DESCRIPTION

FIG. 1 is a left-side view of a first embodiment of a nozzle for textile machine in an open configuration showing my new design, the right-side view being a mirror image thereof;

FIG. 2 is a left-side perspective view of my new design in an open configuration with a component in an unclamped and separated configuration;

FIG. 3 is a left-side perspective view of my new design in the open configuration of FIG. 1;

FIG. 4 is a left-side perspective view of my new design in a closed, clamped configuration;

FIG. 5 is a bottom view of my new design in the configuration of FIG. 4;

FIG. 6 is a top view of my new design in the configuration of FIG. 4;

FIG. 7 is a rear view of my new design in the configuration of FIG. 4;

FIG. 8 is a front view of my new design in the configuration of FIG. 4; and,

FIG. 9 is a left-side perspective view of my new design in the open configuration with a component in an unclamped configuration.

The components in the photographs are depicted in color, however, color is not part of the claimed design.
